UNITED STATES PATENT OFFICE.

RALPH F. MEYER, OF FREEPORT, PENNSYLVANIA.

CLAY-PRESS.

1,373,903.

Specification of Letters Patent.

Patented Apr. 5, 1921.

Application filed May 2, 1919. Serial No. 294,300.

To all whom it may concern:

Be it known that I, RALPH F. MEYER, a citizen of the United States, residing at Freeport, in the county of Armstrong and 5 State of Pennsylvania, have invented certain new and useful Improvements in Clay-Presses; and I do hereby declare the following to be a full, clear, and exact description of the invention, such as will enable others 10 skilled in the art to which it appertains to make and use the same.

This invention relates to improvements in brick presses and it is particularly directed to novel mechanism for forming clay runner bricks.

The principal object of the invention is to provide improved means for simultaneously forming the main channel and side outlet or outlets in a clay runner brick during the formation or molding of the brick.

With the foregoing object outlined and with other objects in view, the invention consists in the novel features hereinafter described in detail, illustrated in the accompanying drawings and more particularly pointed out in the appended claims.

Referring to the drawings:—

Figure 1 is a front view partly in section of my improved mechanism showing the 30 parts in position to receive a ball of clay.

Fig. 2 is a similar view but showing the position of the parts at the completion of the molding operation.

Fig. 3 is a detail view of a modification 35 showing the elements in the positions they occupy at the completion of molding.

Fig. 4 is a similar view of said modification, but showing the positions of the elements after the brick has been formed.

Fig. 5 is a vertical sectional view of a 40 molded brick.

Figs. 6 and 7 are views similar to Figs. 1 and 2 but showing still further modifications.

Figs. 8 and 9 are details of the core and one of the side outlet plungers.

In the embodiment of the invention illustrated in Figs. 1 and 2, 1 designates the frame of the press in which is slidably 50 mounted a vertically movable cross head 2. This cross head is reciprocated by suitable power mechanism (not shown) operating by the rods 3. The cross head carries a mold 4 having a brick ejector 5 provided with an 55 operating stem 6, which is actuated once during each reciprocation of the cross head,

by contacting with the support 7, upon which the frame is mounted.

The mold 4 is provided with a horizontally reciprocating plunger or core 8, which forms 60 the side outlet in the brick, and this plunger has a roller 9 movable in a cam slot 10 provided in a vertically extending stationary post 11. By this mechanism, it will be seen that the plunger 8 will be moved into 65 and out of the mold once during each reciprocation of the cross head. One or more plungers may be used on one side or on all sides of the mold to form one or more side 70 openings at the same time.

Located above the mold 4 is a vertical shaft 12, having a fixed pulley 13, which is belt driven from any suitable source of power. The shaft is provided at its lower end with a fixed core 14 arranged to occupy 75 the central portion of the mold, when said mold is moved into the position shown in Fig. 2, and the core or plunger 8 is milled on its inner end, as shown at 8^a, Fig. 8, to fit the circumference of core 14.

In operation, assuming the mechanism to be in the position shown in Fig. 1 a ball of clay is placed in the mold 4 and rests upon the ejector 5. As soon as the cross head moves upwardly, the ejector is moved into 85 the position shown in Fig. 2 and the ball of clay then drops further into the mold. During the upward movement of the cross head the roller 9 will travel in the slot 10 and move the plunger 8 into the mold, thus forming a depression in the side of the clay ball. Simultaneously the mold brings the clay into engagement with the revolving core 14 and this core forms the central channel of the brick.

When the mold moves downwardly the formed brick will be moved away from the core 14. After the brick in the mold has been partly moved clear of the core 14, the roller 9 will travel in the slot 10 and withdraw the plunger 8 from the mold. Then when the lower end of the rod 6 engages the support 7, the ejector will be brought to a stop and the molded brick will be ejected.

This molded brick is shown in Fig. 5 and 105 it will be seen that it has a central channel 15, which was formed by the core 14, and a side opening 16, that was formed by the plunger or core 8.

In Figs. 3 and 4 is illustrated a modified 110 mechanism for reciprocating the side opening forming plunger 8^a. In this instance,

the plunger moves in a sleeve 20 and a slot 10^a is provided to limit the movement of said plunger. A cam track 10^a is stationarily supported adjacent the path of the mold and its lower end 22 is shaped to catch the roller 9^a as the mold moves upwardly.

The plunger 8 is preferably vented as shown at 8^e in Figs. 8 and 9 to provide an escape for the clay lying between the revolving core 14 and the end of plunger 8 when the two are brought together. This vent may be as large as desired. In some cases it is of advantage to use a release valve as well as a vent, to prevent the suction caused by withdrawal of the plunger, from drawing the side opening out of shape.

In the embodiment of the invention illustrated in Fig. 6, the mold 4^b is stationarily mounted in the frame 1^b and the cross head 2^b is moved toward and away from the mold by means of the rods 3^b. Mounted in the frame is a rotatable but non-axially movable sleeve 50 supported by a bearing 51 and rotated by means of the pulley 13^b. A shaft 12^b is slidably mounted in said sleeve and is prevented from rotating relatively to the sleeve by means of the key 52, which engages a longitudinal slot 53 in the shaft 12^b. The shaft is moved toward and away from the mold by the cross head 2^b and it carries the movable core 14^b. The mold, in this instance, is provided with a plunger 8^a having a roller 9^a, which engages a cam slot 10^b formed in the post 11^b fixed to the reciprocating cross head.

With this construction, a ball of clay is placed in the mold 4^b and the core 14^b is moved down into the mold. As the core descends, the cam slot 10^b will cause the plunger 8^a to move toward the center of the mold for the purpose of forming the side outlet in the brick.

The construction shown in Fig. 7 is similar to that illustrated in Fig. 6, with the exception that the stationary mold 4^c has two side plungers 8^c and the reciprocating cross head 2^c carries a plurality of posts 11^c having cam slots 10^c for reciprocating the plungers.

The foregoing embodiments of my invention are illustrative of the mechanism I em-

ploy and I am aware that various changes may be made in this mechanism without departing from the spirit of the invention as set forth in the claims.

What I claim and desire to secure by Letters Patent is:—

1. In a clay press, the combination with a die member, of a hollow mold adapted to contain plastic material and coöperating with said die member for forming a longitudinal opening in said plastic material, means for moving said mold toward and away from the die member, a plunger movable toward and away from the interior of said mold, and automatically actuated means for reciprocating said plunger.

2. In a clay press, the combination with a core, of a hollow mold movable toward and away from said core, a plunger carried by said mold and movable through one side of the mold, a roller carried by said plunger, and a stationary cam track in which the roller travels during movement of the mold.

3. In a clay press, the combination with a rotatable core, of a hollow mold movable toward and away from said core, a plunger movable through one side of said mold, and automatically operable means for reciprocating the plunger during movement of said mold.

4. In a clay press, a core, a cross head movable toward and away from said core, a mold carried by the cross head and adapted in one position to surround said core, a plunger carried by the mold and mounted for sliding movement toward and away from the interior of the mold, and a stationary cam track located adjacent the path of movement of the mold and engaged by said plunger for reciprocating the latter.

5. In a clay press, the combination with a die member, of a hollow mold member adapted to contain plastic material and coöperating with said die member for forming a longitudinal opening in said plastic material, means for moving one of said members toward the other member, a plunger movable toward and away from the interior of said mold member, and automatically actuated means for reciprocating said plunger.

In testimony whereof I affix my signature,

RALPH F. MEYER.
